UNITED STATES PATENT OFFICE.

WILLIAM T. MESSINGER, OF SOMERVILLE, MASSACHUSETTS.

IMPROVEMENT IN INJECTORS FOR STEAM-BOILERS.

Specification forming part of Letters Patent No. 175,294, dated March 28, 1876; application filed March 10, 1876.

To whom it may concern:

Be it known that I, WILLIAM T. MESSINGER, of Somerville, in the county of Middlesex and State of Massachusetts, have invented a new and useful Improvement in Injectors for Steam-Boilers; and do hereby declare the same to be fully described in the following specification, and represented in the accompanying drawings, of which—

Figure 1 is a front elevation, and Fig. 2 a longitudinal section of an injector with my improvement. Fig. 3 is a transverse section taken through the steam-induct. Fig. 4 is an external view of the inner nozzle with its grooved valve and guides. Fig. 5 is a transverse section of said nozzle taken through its forward guide, while Fig. 6 is an end view of the said nozzle.

In my improvement, the inner steam-nozzle is movable longitudinally, and serves as a valve to close the outer and surrounding nozzle.

In Fig. 2 of the drawings the internal and external steam-nozzles are shown at C and D. The inner nozzle D has fixed on it concentrically a cylindrical valve, A, of a diameter to fit the cylindrical part of the bore of the valve-case B, from which the nozzle C extends.

Between the valve-case B and the steam-induct D' is an arched chamber, E, which at top opens into the induct and at bottom into the valve-case. Within the chamber E is a gear, F, that engages with the cylindrical valve A, which has in its periphery a series of grooves, a' a', that encompass it, at equal distances apart, in order to receive the teeth of the gear and operate therewith, as do the interstices between the teeth of one gear with the teeth of another. The gear F is mounted on a spindle, G, which extends through a stuffing-box, H, and is provided with a handle, H', all being as represented.

Each of the guides a' b' of the inner nozzle,

arranged as shown, approximates in form to that of a triangular prism, its purpose being to guide the nozzle D rectilinearly and concentrically within the case B and nozzle C, and to allow steam to pass freely to the nozzles, as occasion may require.

By taking hold of the handle H' and turning it so as to revolve the spindle one way, the nozzle D may be advanced within the nozzle C, so as to close it for the passage of steam through it. When the nozzle C is so closed, the valve A will have been advanced far enough for the steam to pass into the rear end of the nozzle D, and thence entirely through such nozzle.

On turning the handle so as to cause the nozzle D and its valve A to be moved backward far enough, the steam may be cut off from passing into the nozzle D, and be made to flow only through, and be discharged by, the nozzle C. The tube or nozzle D is formed conical or tapering at and near its front end, as shown, in order for it to constitute a valve to more or less close the terminus of the nozzle C.

From the above it will be seen that, by a proper adjustment of the valve A and nozzle D, the steam may at one time be caused to flow through both nozzles, or it may be entirely shut off from either of them and caused to pass through the other.

I claim—

In the injector for steam-boilers, the combination of the stationary nozzle C and the movable nozzle D and the valve A thereof, applied to the case B and steam-induct D', and provided with operative mechanism, all being substantially and to operate as specified.

WM. T. MESSINGER.
